S. C. Ellis INVENTOR

UNITED STATES PATENT OFFICE

CARLETON ELLIS, OF MONTCLAIR, NEW JERSEY, ASSIGNOR TO ELLIS-FOSTER COMPANY,
A CORPORATION OF NEW JERSEY

BEVERAGE CONTAINER

Application filed March 23, 1927. Serial No. 177,601.

This invention relates to milk bottles and similar beverage containers, and relates especially to a container comprising a wide-mouthed bottle having a flanged or beaded top, a paper disc stopper therefor, and a waxed paper tumbler, which, preferably is approximately the size of an ordinary glass tumbler, said paper tumbler being carried in an inverted position on the upper part of the bottle and being held in place against the side walls thereof by constriction for a considerable distance below the bottle flange.

The accompanying drawings show in an illustrative manner the container of the present invention.

In the drawings Figure 1 is an elevation of a bottle of the milk bottle type, and Figure 2 is a similar bottle showing the upper part thereof in cross section.

Like reference characters denote like parts in these drawings.

In the drawings A is a glass bottle having a flanged or beaded top or rim, as shown, the mouth having a seat carrying a paper disc seal B. C is an inverted receptacle or tumbler fitting neatly around the rim or flange of the bottle and constricted beneath it, as shown at E. The tumbler has plaits or folds as shown at D. Preferably the upper rim of the tumbler is rolled very slightly away from the walls of the bottle as shown at F.

The paper tumbler is waxed or otherwise rendered water-resistant. Various waxes may be used for impregnation, such as paraffin wax, ceresin wax, carnauba wax, Montan wax, rosin or other resins, or mixtures of rosin, and the like, with any of the waxes aforesaid. Mixtures of waxes likewise may be used. Calcium or magnesium stearate or compositions containing these waterproofing materials also may be employed.

In certain copending applications I have set forth various forms of containers capped with what is known as hood caps. These, in general, are made of relatively heavy paper, and in particular of coarse paper prepared from ground wood and sulphite pulp. The caps are intended merely to cover the mouth of the bottle to protect it from dust and to

serve as a seal. Heavy paper which will carry a large amount of hard wax binder preferably is used in order to have present enough binder to give the requisite sealing effect. When such hood caps on the bottle are exposed to dampness the sealing effect often quickly disappears and the hood cap may in fact loosen and unfold in the course of a few hours in contact with water.

In the present invention, instead of having simply a shallow tumbler or tray secured around merely the bottle rim, I employ a receptacle of substantial depth, the walls of which preferably having a height considerably greater than the base when said receptacle is placed upright ready to receive a liquid. By so proportioning the height to diameter, a paper tumbler is obtained as aforesaid, which has the two-fold function of serving as a drinking glass and also having sufficient area of contact with the sides of the bottle to remain quite firmly in place, even under severe conditions of moisture.

The tumbler is applied to the bottle by sliding it over the bottle mouth and then constricting the portion below the flange to obtain a neat fitting effect, as indicated by the drawings. The waxed tumbler may be heated before it is applied and on being clamped when still warm will quickly harden in contact with the cold walls of the bottle and remain shaped thereto.

Preferably I employ paper which is white in color and as a binder preferably paraffin wax of high quality. In this way a tumbler which is white in appearance, giving an attractive effect to the container results.

In the employment of so-called hood caps, it has been proposed to employ hard waxes as the binding agent in order to prevent fouling of the bottles by adherence of a softer and unsaponifiable wax such as paraffin wax.

In the present invention, owing to the large area of contact of the paper tumbler with the sides of the bottle, there is no occasion for so powerful and concentrated a binding effect. Therefore, I may employ paraffin wax in quantity sufficient to produce a good waterproofing effect, so that the tumbler may be employed for drinking purposes on with-

drawal from the bottle. By using only a moderate proportion of paraffin wax, it is not squeezed out of the paper on clamping, and therefore does not foul the bottle. This 5 enables the employment of a cheap wax and one which, moreover, is white in color, whereas, most of the high melting point hard waxes are not white, and their employment tends to discolor the paper. This is especially true 10 when such waxes are employed with a ground wood paper stock, such as that referred to above.

Paper which I prefer to employ in the practice of the present invention is a high 15 grade bleached sulphite pulp stock of good strength and having a thickness of about 0.1 to 0.13 mm.

What I claim is:

1. A container for milk comprising a wide-
20 mouthed bottle having a flanged top, a paper disc stopper therefor, and a waxed paper tumbler of approximately the size of an ordinary glass tumbler, said paper tumbler being carried in inverted position on the upper part 25 of the bottle and being held in place against the side walls thereof by constriction for a considerable distance below the bottle flange.
2. A container for milk comprising a wide-
30 mouthed bottle having a flanged top, a paper disc stopper therefor, and a paraffined paper tumbler carried in inverted position on the upper part of the bottle and being held in place against the side walls thereof by constriction for a considerable distance below the bottle flange.

CARLETON ELLIS.
